INVENTOR

UNITED STATES PATENT OFFICE.

WILLIAM HARRISON ALBACH, OF NEW YORK, N. Y.

DESIGN FOR A STOVE.

SPECIFICATION forming part of Design No. 29,074, dated July 19, 1898.

Application filed March 30, 1898. Serial No. 675,808. Term of patent 3½ years.

To all whom it may concern:

Be it known that I, WILLIAM HARRISON ALBACH, a citizen of the United States, and a resident of New York city, in the county of New York and State of New York, have invented and produced a new and original Design for Stoves, of which the following is a specification.

Figure 1 is a perspective view of my stove. Fig. 2 is an enlarged longitudinal sectional view of the same.

As shown in the drawings, the leading feature of my design consists of the body of the stove, which comprises a bottom plate A, resting on detachable legs F, with feet f, a top plate C, with edge grooves or trough c, and

lugs n on upper surface around suitable openings, a plurality of cones E, arranged as shown in Fig. 2, a siding B, a space between said siding and top plate, and bolts D, arranged as shown in Fig. 2.

What I claim is—

The design for a stove as herein shown and described.

Signed at New York, in the county of New York and State of New York, this 26th day of March, A. D. 1898.

W. HARRISON ALBACH.
